UNITED STATES PATENT OFFICE.

ARTHUR C. E. STROM, OF ORTEGA, FLORIDA.

GYMNASIUM APPARATUS.

Application filed August 17, 1925. Serial No. 50,813.

This invention relates to a gymnasium apparatus particularly adapted for chinning with one hand; and it is especially efficient in developing the biceps; it is perfectly adjustable for use by persons of different stature and strength—a very important adaptation in gymnasium apparatus.

Fig. 1 is a view in side elevation of the supporting column and handle associated therewith showing floor-plate or column base for bolting down and top cap and foot rest in approximate positions.

Fig. 2 is a side view of the bracket forming part of the foot rest shown in Figs. 4 and 5.

Fig. 3 is a perspective view of the auxiliary support for use with the foot rest shown in Figs. 4 and 5.

Fig. 4 is a perspective view of the completely assembled apparatus and showing a person using the same.

Fig. 5 is a front view of the foot rest.

Numeral I, in said drawing, is the supporting column threaded at both ends in order to be reversible for wear, it has lateral holes bored through and through as illustrated. Numeral II is the supporting arm or handle to be inserted into the laterally bored holes in column. The reference character III designates the foot rest to be used in conjunction with the supporting column as illustrated in Fig. 4. Numerals IV, V, and VI, are respectively the column base, the ring or washer for adjustable alignment, and, the top cap.

To train oneself for one-hand chinning, on this apparatus, grasp the supporting arm or handle near the outer extremity with but one hand and place the feet upon one of the rungs of the foot rest (accordingly as a person desires to strain himself), then let the

body slowly sink to the floor—that is to say, until the buttock touches the floor—after which attempt to draw the body upward until the chin touches the handle, the while keeping the knees rigid as at the angle assumed at the start. (Note Fig. 4 of drawing.) The auxiliary rung, Fig. 3, is to be placed upon the principal foot rest when a person has advanced sufficiently to be nearly ready to try one-hand chinning on an overhead horizontal bar. Any degree of stress and strain on the biceps is possible with this apparatus. It is progressive up to nearly the entire bodily weight.

I claim:

1. A one-hand chinning apparatus comprising a vertical column having a series of longitudinally spaced openings extending horizontally therethrough, a supporting arm adapted to be selectively inserted in said openings, said arm having hand grips formed at one end thereof, and a foot rest, comprising a series of rungs in a frame, associated with said column and supporting arm and adapted to support the user of the device.

2. A one-hand chinning apparatus comprising a vertical column having a series of longitudinally spaced openings extending horizontally therethrough, a supporting arm adapted to be selectively inserted in said openings, said arm tapering from inserting end to outward end—thus giving various sized hand grips without any defined handles, and a foot rest, comprising a series of rungs in a frame, associated with said column and supporting arm and adapted to support the user of the device.

In testimony whereof I affix my signature.

ARTHUR C. E. STROM.
